UNITED STATES PATENT OFFICE.

JOHN D. MACLACHLAN, OF CHADWICK, MISSOURI.

FIRE-TUBE BOILER.

1,304,496.

Specification of Letters Patent. Patented May 20, 1919.

Application filed May 7, 1918. Serial No. 233,120.

To all whom it may concern:

Be it known that I, JOHN D. MACLACHLAN, a citizen of the United States, residing at Chadwick, in the county of Christian and 5 State of Missouri, have invented certain new and useful Improvements in Fire-Tube Boilers, of which the following is a specification.

This invention relates to water heaters, and more especially to water tube boilers of the internal fire tube type; and the object 10 of the same is to increase the heating capacity of a boiler of this type.

Another object is to provide for expansion and contraction, and yet another object 15 is to provide a support for the tubular boiler within its casing.

Yet other objects will appear in the following specification and claim, and reference is made to the drawings herewith and 20 in which:

Figure 1 is a section through the casing and an elevation of the boiler, partly broken away,

Fig. 2 is a horizontal section on the line 25 2—2 of Fig. 1.

Fig. 3 is a plan of one annulus,

Fig. 4 is a plan of the disk,

Fig. 5 is an enlarged section of one of the 30 compound tubes, made up of an external water pipe and an internal flue.

While this boiler yet to be described may be incased in masonry or in metal with or without a jacket, for purposes of illustration I have shown an upright cylindrical casing or shell S having a grate G at its lower end and an outlet O at its upper end for the products of combustion. I would not be limited in this particular, nor in the exact construction of parts as yet to be 35 described, nor in fact to the vertical dispositions of the tubes, as they might be horizontal or otherwise. The water feed pipe is indicated at F, the steam dome at D, and the main steam outlet pipe at M. An indicator I is shown in the form of a water glass wherein may be seen the level of the water in the boiler at any time. There may be other attachments such as a pressure gage, but these 40 details are not necessary of amplification.

Coming now to the present invention, I provide upper and lower hollow headers 1 and 2 supported by brackets 3 within the shell S and preferably connected by long bolts or rods 4 so as to hold them in proper 45 spaced relation. Each of the headers comprises upper and lower sections formed with

outer abutting flanges which are pierced to receive the rods 4 upon which are mounted pairs of nuts 4¹ between which the sections of the respective headers are clamped. 60

The rods 4, besides serving as clamping means for the sections of the headers act as ties to connect the headers and secure them to the brackets 3 which form supporting means therefor. The feed pipe F opens into 65 the bottom of the lower header and may also be used for clean-out purposes. From the center of the upper header a pipe leads into the steam dome as shown. These headers

are preferably circular, and they are connected with each other at their centers by a comparatively large water pipe 5 through which the circulation will be downward as indicated by the arrows. The gist of my invention, however, lies in connecting the contiguous walls of the headers by a series of 70 water pipes 6, and connecting the relatively outer sides of the two headers by a series of tubes 7 smaller than the tubes 6 and constituting flues. Their lower ends are open at 8 75

to receive the heat rising from the fire upon the grate, and their upper ends 9 open into the space beneath the steam dome, around which pass the products of combustion to the outlet O. Between the exterior of the 80 pipes 6 and the interior of the pipes 6 is a relatively thin annular space 10 through which the water flows from the lower header upward into the upper header, returning down the central pipe 5 as the 85 arrows indicate. Manifestly this thin tube of water (if I may call it such) is intensely heated by the products of combustion passing upward through the internal flue, beside which tongues of flame may pass around 90

the edges of the lower header and through the spaces 11 between the several water pipes 6, as I do not let them contact with each other exteriorly. I may say that no tube is in contact with any other tube, and 95 therefore, I provide for expansion and contraction under varying conditions of heat. The water pipes are headed into the inner plates of the headers, and the flues are headed through the outer plates thereof. If the 100 parts are built substantially on the proportion shown (although I do not wish to be limited in this particular) I have found by experiment that the circulation is so rapid that scale cannot collect in the tubular water 110 space between the two pipes. Also the bore of the flue is so ample that the accumulation

of soot therein is unlikely or at least very slow, and cleaning out need be resorted to but seldom.

I have suggested that the headers may be supported on brackets 3 within the shell 2. In addition I may provide means for spacing the pipes 6 from each other. At appropriate points annular disks or annuli 20 are provided, carried on brackets 23 which are secured inside the wall of the shell, these annuli being pierced with holes 21 disposed in concentric rings and fitting around the two outermost series of pipes 6. Also I provide between the annuli a disk 25 having other holes 26 fitting around the pipes in all series. In Fig. 1 it will be observed that the pipes passing through the outer holes in the disk pass also through the inner ring of holes in the annuli, and the latter are thus tied to the disk. The disk is supported by collars 21 on this ring of pipes. Under the intense heat to which this device is subjected it may be wise to provide some means for keeping the pipes separated from each other so as to permit the passage of heat through the spaces 11, whence it radiates through the walls of the pipes 6 to the annular water space 10. In order to keep the concentric pipes equally spaced, or in other words to keep the flues 7 at the center of the pipes 6, I may provide one or the other with ribs as shown at 27 in Fig. 5, the same projecting from one element into contact with the other. These ribs may be continued throughout the length of the pipes or disposed at intervals as desired, but I would not make the tip or ridge of the rib contact with the adjacent element so closely that one tube or pipe could not be withdrawn from the other. This of

course becomes necessary at times when leaks arise, and a flue or pipe needs substitution or repair.

The foregoing description and the drawings have reference to what may be considered the preferred, or approved form of my invention. It is to be understood that I may make such changes in construction and arrangement and combination of parts, materials, dimensions, et cetera, as may prove expedient and fall within the scope of the appended claim.

Having thus fully described my invention, what I claim as new and desire to secure by Letters Patent:—

A water tube boiler, comprising an upright casing, brackets extending inwardly from the walls of the casing at different elevations, upper and lower headers, each embodying upper and lower sections formed with abutting flanges, rods forming ties between the headers and connecting them to the lowermost set of brackets, nuts on the rods clamping the sections of the respective headers and securing them to the lowermost brackets, water pipes connecting the water spaces of the headers, tubes passing through the water pipes and headers and secured to the outer walls of the latter, annular disks supported upon the upper brackets and having the outer water pipes and the tie rods passing therethrough and an intermediate disk having the inner water pipes passing therethrough and supported thereon.

In testimony whereof I affix my signature in presence of two witnesses.

JOHN D. MacLACHLAN.
